US00D571334S

(12) **United States Design Patent** (10) **Patent No.:** **US D571,334 S**
Chung et al. (45) **Date of Patent:** **** Jun. 17, 2008**

(54) **PORTABLE PHONE**

(75) Inventors: **Jae-Woong Chung**, Seongnam-si (KR);
Ki-Sung Kim, Seoul (KR);
Yoon-Young Cho, Seoul (KR);
Chang-Hwan Hwang, Goyang-Si (KR)

(73) Assignee: **Samsung Electronics Co., Ltd.**,
Suwon-Si (KR)

(**) Term: **14 Years**

(21) Appl. No.: **29/266,237**

(22) Filed: **Sep. 18, 2006**

(30) **Foreign Application Priority Data**

Mar. 17, 2006 (KR) 30-2006-0009985

(51) **LOC (8) Cl.** **14-03**

(52) **U.S. Cl.** **D14/138**

(58) **Field of Classification Search** D14/137,
D14/138, 147, 218, 247-248, 341-347; 455/556.1,
455/566, 575.1, 575.3
